UNITED STATES PATENT OFFICE.

GEORGE H. TABER, OF BINGHAMTON, NEW YORK.

SPRING COVER AND LUBRICATOR.

1,387,024.

Specification of Letters Patent.

Patented Aug. 9, 1921.

Application filed January 24, 1921. Serial No. 439,352.

To all whom it may concern:

Be it known that I, GEORGE H. TABER, a citizen of the United States, residing at Binghamton, in the county of Broome and 5 State of New York, have invented certain new and useful Improvements in Spring Covers and Lubricators, of which the following is a full, clear, and exact description.

The present invention relates to an improved automobile accessory in the form of a shield device and lubricator for the springs.

Automobile springs, by reason of their construction and location, have been found to be difficult to lubricate and in addition 15 difficulty is experienced in retaining the lubricant between the spring leaves. The springs are constantly exposed to the action of mud and water which works in between the leaves forcing out the lubricant and causing rust- 20 ing and loss of resiliency. To effect proper lubrication of these springs it has been the practice to wrap the same with cloth and apply lubricant thereto. Covering the cloth has likewise been proposed to eliminate the 25 free access of mud and water thereto.

The present invention relates to an improved spring cover which is simple, inexpensive to manufacture and assemble and which may be readily applied to a spring 30 without the use of tools.

Other objects of the invention reside in the provision of a cover which is flexible and adapted to yield to conform to the deflection of the springs under load. The 35 cover is furthermore of such contour that it improves the general appearance of the spring, and effectually hides the wrapping.

I further provide a novel lubricating wrapping which may be readily placed in 40 position within the cover and retained properly upon the spring.

Other objects and advantages will be set forth in more detail in the accompanying specification and shown in the drawings, in 45 which:

Figure 1 shows a side elevation of a spring equipped with my improved cover and lubricating wrapping. Certain parts are shown broken away to show the interior construction.

Fig. 2 is a sectional view taken on line 2-2 of Fig. 1, and shows the method of retaining the cover in place.

Fig. 3 is a sectional view taken on line 50 3-3 of Fig. 1 and shows in section the

lubricating wrapping and an end view of the retaining clip therefor.

Fig. 4 shows a perspective view of the central cover section.

Fig. 5 is a perspective view of one of the 60 end cover sections.

Fig. 6 is a perspective view of the lubricating wrapping.

Fig. 7 is a view showing the clip devices 65 for retaining the cover in place.

In more detail, the cover proper consists of two identical end sections 10 and a middle section 11. Both are of inverted U or trough shaped cross section open at the bottom and having smooth top and side walls, the 70 latter being shaped to conform to the general curvature of the spring. The middle section is apertured at 12 to permit the bumper 13 to extend therethrough and this section is adapted to cover up entirely the 75 section of the spring adjacent the axle and spring clips. At the ends of part 11 the metal is reversely bent, as shown at 14, to form a recess for the reception of the end of the end section. The extended end 15 acts 80 as a spring anti-rattler, preventing objectionable vibration between parts 10 and 11.

The end sections 10 are identical. Each section, at its inner end, is provided with curved ears 16 which securely retain a U- 85 shaped clip 17 in place and also serve as a reinforcement for the cover. The U-shaped clip is of spring metal and provided with sharpened beveled prongs 18, adapted to permit the clip to be forced down over the 90 leaves of the spring and snap into the grooves between the curved edges of the leaves. The clip 17 also acts as a reinforcement for the cover. The prongs engage the spring relatively low down and therefore 95 act as a pivot for the end sections of the cover, these sections rocking about these points as the spring deflects under load. The recess 14 is of such character as to allow of this movement of the cover plates. 100

The outer end of the cover is substantially similar to the inner end. A similar clip 17 is provided, retained in a similar way on the cover by the ears 16 and engaging between the spring leaves as before. The horizontal 105 ear is provided with an extension in the form of a spring foot 19 which forms an anti-rattler support for the cover and prevents water and dirt from flowing down the top of the spring into the cover. 110

- The lubricating wrapping is entirely independent of the cover and comprises a piece of bagging or cloth 20, of suitable character to retain the maximum of oil. This cloth is carried by a pair of spring metal arms 21 which crimp about the cloth as shown in Fig. 3. These arms are joined at the ends by clips 22 which are retained by bending back the arms 21 thereover as shown at 23.
- 10 The metal parts 21 and 22 constitute a carrying frame for the cloth and permit the wrapping to be readily placed in position on the spring. After the parts are thus assembled the flap end of the cloth is tucked under the arm 21 (see Fig. 3), thereafter the ends of clips are bent over the top of the spring and secured together by passing them through and bending back over slotted locking washers 24 (see Figs. 3 and 7). I preferably bend the arms 21 slightly outwardly to clear the leaf clip 25 and the cloth may be cut away at this point as shown, if desired.

It will be understood that the lubricating cover is first secured in place in the manner described. Thereafter the cover is impregnated with oil in any desired way. The metallic cover sections are then applied by hand. Once in place these metallic sections are kept out of contact with the cloth covers, thereby preventing wear of the cloth and are also out of contact with the spring except at certain desired points of contact. Undue and improper wear of the cover is thereby prevented.

The metallic cover sections are easily removable for reoiling or replacing cloth wrappings and when in place prevent water and mud from running down the springs and washing off the oil therefrom. After once assembled the device presents no bolts or projections which would tend to collect dirt or injure the hands of the washer and the appearance of the spring assembly is materially improved.

What I claim is:

1. In a device of the class described, in combination, a trough-shaped member adapted to house an end portion of a spring, and clip members carried thereby having prongs adapted to engage the spring between the leaves thereof and to thereby secure the trough-shaped member in position thereon.
- 55 2. In a device of the class described, in combination, a spring cover comprising a middle inverted trough member and a pair of end members of the inverted trough section, said end members engaging said middle members, and clip devices carried by said end

members for detachably securing said cover assembly to the leaves of a spring.

3. In a device of the class described, in combination with a spring, of a trough-shaped member shaped to conform to the curvature 65 of the spring and covering the top and sides thereof, a clip device carried thereby and provided with prongs to engage between the leaves of said spring, said prongs disposed adjacent the spring center forming a pivot 70 about which the trough-like member may swing when the spring is deformed.

4. In a device of the class described, an open-bottomed housing for a leaf spring, comprising a pair of end members and a 75 middle member, said end members having means for detachably clipping the same to the spring leaves, said middle member having extending tongues engaging said end members and securing said member in position.

5. The invention set forth in claim 4 in which the end members are adapted to pivotally swing about their point of support and in which the tongues are adapted to permit a relative longitudinal movement between the top portions of the end and middle members.

6. In a device of the class described, in combination with a leaf spring, of a lubricating means therefor comprising a fibrous lubricant retaining means, and frame for the same, said frame comprising a pair of longitudinally extending arms having means thereon for detachably securing the 95 wrapping in position upon the spring.

7. In a device of the class described, in combination, a lubricating means for a leaf spring comprising a lubricant-retaining wrapping, a frame for the maintaining of 100 the same in contact therewith said frame comprising a pair of spaced arms extending longitudinally along the spring, and clips associated with the arms to interconnect the same and to detachably secure the frame 105 to the spring.

8. The invention set forth in claim 7 in which a cover device is provided for shielding the wrapping from water and mud.

9. A cover and lubricating device for a 110 leaf spring comprising a wrapping adapted to maintain lubricant and supply the same to the spring, and a cover member protecting said wrapping and secured to the spring, said cover member having means to space 115 the same from the wrapping whereby wear of the latter is avoided.

In testimony whereof I hereunto affix my signature.

GEORGE H. TABER.
